ANTI-FREEZE TESTER

Joseph R. Mango, Midlothian, Ill., assignor to Mid-Continent Manufacturing Co., Springfield, Ohio, a corporation of Ohio

Filed Aug. 3, 1965, Ser. No. 86,410

Term of patent 14 years

(Cl. D52—7)

FIGURE 1 is a front elevation of an anti-freeze tester embodying a new design;

FIGURE 2 is a elevation of the left side of the anti-freeze tester of FIGURE 1, the anti-freeze tester appearing the same from the opposite side;

FIGURE 3 is a bottom view of the anti-freeze-tester of FIGURE 1;

FIGURE 4 is a rear elevation of the anti-freeze tester of FIGURE 1;

FIGURE 5 is a top view of the anti-freeze tester of FIGURE 1; and

FIGURE 6 is a fragmentary section taken along line 6-6 of FIGURE 1.

The essential features of the design reside in the portions shown in full lines.

I claim:

The ornamental design for an anti-freeze tester, substantially as shown and described.
